CLAIM

The ornamental design for a console phonograph record cleaner cover plate, as shown and described.

DESCRIPTION

FIG. 1 is a top perspective view of a console phonograph record cleaner cover plate, showing my new design;

FIG. 2 is a right side elevational view shown on a slightly smaller scale, the left side being a mirror image thereof;

FIG. 3 is a cross-sectional view on line 3—3 of FIG. 1;

FIG. 4 is a bottom plan view thereof;

FIG. 5 is a front elevational view thereof;

FIG. 6 is a rear elevational view thereof.

The broken line disclosure of a phonograph console in FIG. 1 is for illustrative purposes only and forms no part of the claimed design.
